RING TRAVELLER

Charles Robert Langston, Jr., Seneca, S.C., assignor to
Coats & Clark, Inc., New York, N.Y.

Filed Sept. 4, 1973, Ser. No. 394,381

Term of patent 14 years

Int. Cl. D8—08

U.S. Cl. D8—248

FIG. 1.

FIG. 2.

FIG. 3.

FIG. 5.

FIG. 6.

FIG. 7.

FIG. 1 is a side elevational view of a ring traveller showing my new design;
FIG. 2 is an elevational view of the other side thereof;
FIG. 3 is a top view of FIG. 1;
FIG. 4 is a bottom view of FIG. 1;
FIG. 5 is a front view of FIG. 1;
FIG. 6 is a back view of the left side of FIG. 1; and
FIG. 7 is a cross sectional view through line 7-7 of FIG. 1.

I claim:
The ornamental design for a ring traveller, substantially as shown and described.
